UNITED STATES PATENT OFFICE.

GUSTAV J. GRUENDLER AND WILLIAM A. MELETIO, OF ST. LOUIS COUNTY, MISSOURI.

REFRIGERATOR.

Application filed November 9, 1925. Serial No. 67,877.

Our invention relates to refrigerators and more particularly to refrigerators of the display or show case type.

Heretofore refrigerators of this type have had one storage compartment therein and in which all of the food-stuffs to be preserved were placed. However, these food-stuffs were of a widely different character in that some required an almost freezing temperature for preserving them and to prevent decomposition while others of the food-stuffs could be preserved equally as well at a higher temperature. However, since these refrigerators had only one storage compartment the whole storage compartment had to be maintained at the temperature required to preserve the most perishable food-stuffs stored therein with a resultant great waste of ice.

The object of our invention is to provide a refrigerator in which two storage compartments are used and which storage compartments are maintained at different temperatures and are adapted to preserve different classes of food-stuffs.

Our invention is fully shown in the accompanying drawings wherein similar letters are used to designate similar parts: Fig. 1 is a top view of the refrigerator; Figs. 2, 3 and 4 are front, back and end views, respectively, of the refrigerator; Fig. 5 is a section along the lines 5—5 in Fig. 1; Fig. 6 is a section along the lines 6—6 in Fig. 1; Fig. 7 shows a detail of construction and Figs. 8, 9 and 10 show a refrigerator embodying a modified form of some of the parts.

Referring to the figures the refrigerator shown therein and including one embodiment of our invention comprises an upper or primary storage compartment A and a lower or secondary storage compartment B separated therefrom. The upper storage compartment A has a back wall C having the service doors D hingedly mounted thereon each of which is normally held in closed position by a catch E. The storage compartment A also has a top wall F, a front wall G and end walls H all of which in this form of our invention consist of glass plates arranged as shown. In the rear wall of the lower storage compartment B are the doors J, normally held in closed position by addi-

tional catches E. The front wall of the storage compartment B is provided with a transparent panel K. The upper and lower compartments A and B are separated by a wall X which is preferably insulated with cork or any other suitable material, as shown in Figs. 5 and 6, for the purpose hereinafter explained.

The refrigerating means for cooling the two compartments of the refrigerator, as shown in this embodiment, comprises a primary cooling medium positioned in the upper storage compartment A and a secondary cooling medium positioned in the lower storage compartment B. The primary cooling medium consists of an ice container L, preferably of metal, positioned in the bottom of the upper storage compartment A and substantially co-extensive therewith, as shown. The ice container L in this form of our invention is adapted to receive blocks of ice, but in other forms of our invention it may be charged with cracked ice and salt. The bottom of the container L is pitched transversely to the middle, as shown in Fig. 6, and longitudinally to one end, as shown in Fig. 5, so that the water resulting from the melting of ice in the container will pass out of the drain opening M at the lower end of the ice container and will pass downwardly through the drip pipe N into the receptacle of the secondary cooling medium in the other compartment.

The secondary cooling medium is adapted to cool the lower storage compartment B and comprises a receptacle which may be of any form but which in the embodiment of our invention shown in Figs. 1 to 7, inclusive, consists of a tank O which is positioned to receive and hold the cold water as it comes out from the lower end of the drip pipe N. A drain pipe P, preferably threaded in a boss Q in the bottom of the tank O, as shown in Fig. 7, is arranged to drain the excess water from the tank O after the level of the water in the tank has almost reached the top thereof, as clearly shown in Fig. 6. The drain pipe P discharges into an outlet pipe R through which the water passes out of the refrigerator. We prefer that the drip pipe N extends downwardly a sufficient distance into the tank O and that the drain pipe P

is arranged so that the level of the water in the tank O will at all times be sufficient to submerge the lower end of the drip pipe N. We also prefer that the tank O be constructed, as shown in detail in Fig. 7, so that it may be readily removed from the refrigerator to be cleaned.

The modified form of the receptacle for receiving and holding the cold water resulting from the melting of the ice in the ice container L of the primary cooling medium, as shown in Figs. 8 to 10, inclusive, consists of a coil pipe S preferably arranged along the top of the lower compartment B and having at one end the inlet header T arranged to receive the water as it comes downwardly through the drip pipe N and at the other end having the outlet header U which has the drain pipe V extending downwardly therefrom and emptying into the outlet pipe R. The outlet header U and the drain pipe V are constructed to trap the cold water in the coil pipe S and maintain the pipe at all times filled and the inlet header T is arranged so that the water therein will submerge the lower end of the drip pipe N.

The operation of the refrigerator embodying our invention is as follows:

In the form of the refrigerator shown the upper storage compartment is adapted to receive fish or other highly perishable food-stuffs which are laid on top of and in contact with the ice in the ice container L. Since the upper storage compartment A has the ice container L therein, it will be cooled to a comparatively low temperature by this primary cooling medium and the perishable food-stuffs placed therein will be preserved. As the ice in the ice container L melts the cold water resulting from the melting of the ice, as explained above, passes out through the opening M and downwardly through the drip pipe N into the cold water receptacle which may be the tank O, the coil pipe S, or in any other suitable form. As set forth above, both in the tank O and the coil pipe S the cold water is trapped therein so that the cold water receptacle is at all times substantially filled with cold water and, also, the cold water as it enters the receptacle through the drip pipe N is discharged into the receptacle below the level of the water therein. The cold water in this receptacle will chill the receptacle and will cool the lower storage compartment B but, of course, not to the same low temperature as the upper storage compartment A is cooled by the ice in the ice container L. The lower storage compartment is adapted to receive less perishable food-stuffs, smoked fish and meats, cheese, butter, and the like, which do not require a low temperature for their preserving.

It can be readily seen that since the upper storage compartment only is cooled to the low temperature necessary to preserve

highly perishable food-stuffs and that, since the lower storage compartment B is separated from the compartment A by the wall X and is cooled by the auxiliary cooling medium comprising a cold water receptacle and complementary pipes and fittings, the ice consumption in a refrigerator embodying our invention will be much less than a refrigerator of the old type having the same storage space.

Also, if the coil pipe S is used to receive and hold the cold water resulting from the melting of the ice and the coil is positioned along the top of the storage compartment B, as shown, the air in the top of the refrigerator will be cooled and will fall to the bottom so that a more even temperature in the compartment B will be maintained.

We do not propose to limit our invention to the exact details of construction shown in the drawings and described above. As we have stated only one embodiment of our invention has been set forth herein and the construction, shape and arrangement of the various parts may be varied within wide limits without deviating from the spirit of our invention.

What we claim as new and desire to secure by Letters Patent, is:—

1. A refrigerator having a primary compartment having an ice container therein and a secondary compartment having a receptacle consisting of a coil pipe positioned along the top thereof and adapted and arranged to receive and hold liquid resulting from the melting of ice in said ice container, a drip pipe arranged to carry said liquid from said ice container and discharge it into one end of said coil pipe and a drain pipe adapted and arranged to maintain a predetermined level of liquid in said receptacle and to allow the surplus liquid to drain from said receptacle at the end thereof opposite the end into which the liquid is discharged from said ice container.

2. A refrigerator having a plurality of separated compartments positioned one above the other, a portion of the wall of each of said compartments being of transparent material, an ice container positioned in the uppermost of said compartments and another of said compartments having therein a receptacle positioned along the top thereof and adapted and arranged to receive and hold liquid resulting from the melting of ice in said ice container.

3. A refrigerator having upper and lower storage compartments, an ice container extending along and substantially coextensive with the bottom of said upper compartment, and the lowermost of said compartments having therein a receptacle consisting of a coil pipe positioned along the top thereof and adapted and arranged to receive and hold liquid resulting from the melting of

ice in said ice container, a drip pipe arranged to carry said liquid from said ice container and discharge it into one end of said coil pipe, and a drain pipe adapted and arranged to maintain a predetermined level of liquid in said receptacle and to allow the surplus liquid to drain from said receptacle

at the end thereof opposite the end into which the liquid is discharged from said ice container.

In witness whereof we have signed our names to this specification.

GUSTAV J. GRUENDLER.
WILLIAM A. MELETIO.
